UNITED STATES PATENT OFFICE.

JOHN SLATER, OF BURSLEM, COUNTY OF STAFFORD, ASSIGNOR TO
GILDEA & WALKER, OF DALE HALL, BURSLEM, ENGLAND.

DESIGN FOR A VEGETABLE-DISH.

SPECIFICATION forming part of Design No. 13,295, dated September 12, 1882.

Application filed August 8, 1882. Term of patent 3½ years.

To all whom it may concern:

Be it known that I, JOHN SLATER, of Burslem, England, have invented a new and original Design for a Vegetable-Dish, of which the following specification is a full, clear, and exact description, reference being had to the accompanying drawing, forming part of this specification.

The drawing represents a perspective view of a vegetable-dish having my new design.

This invention relates to a new configuration for a vegetable-dish or other china household article, such as a tureen, sauce-boat, pitcher, tea-pot, or sugar-dish.

15 It consists of a dish, A, made of rectangular form, the two opposite sides *a a'* and *b b'* being parallel and joined by rounded corners. Each side is composed of an upper straight section, *c*, a central curved section, *d*, and a 20 lower straight section, *e*. The curve of the central section, *d*, is such that it projects outwardly near its top, and thence recedes inwardly toward the bottom, so that the base of the dish is smaller than its top.

f is one of the handles applied to the dish. 25

If the design is to be applied to a pitcher, the shape of the upper straight portion, *c*, is modified so as to run out into a nozzle.

I claim as my invention—

1. The design for a rectangular vegetable-dish having upper straight section, *c*, central curved section, *d*, and lower straight section, *e*, substantially as shown. 30

2. The design for a rectangular vegetable-dish having straight top and a section, *d*, 35 curved first outward and then inward in such manner that the base of the dish is smaller than its top, substantially as shown.

3. The design for a vegetable-dish having parallel sides *a a'* and parallel sides *b b'*, and 40 composed of the sections *c d e*, substantially as shown.

JOHN SLATER.
